UNITED STATES PATENT OFFICE.

CLARENCE T. MAPES, OF CRAFTON, PENNSYLVANIA.

DEVICE FOR CUTTING WIRE CABLES.

SPECIFICATION forming part of Letters Patent No. 729,951, dated June 2, 1903.

Application filed December 17, 1902. Serial No. 135,638. (No model.)

To all whom it may concern:

Be it known that I, CLARENCE T. MAPES, a citizen of the United States of America, residing at Crafton, in the county of Allegheny 5 and State of Pennsylvania, have invented certain new and useful Improvements in Devices for Cutting Wire Cables, of which the following is a specification, reference being had therein to the accompanying drawings.

This invention relates to certain new and useful improvements in devices for cutting wire cable, and relates particularly to a tool or device adapted to be lowered into an Artesian well, oil-well, gas-well, or the like for cutting the wire cable at a point in close proximity to the rope-socket in order that the grab or other device employed in removing the tools may be readily engaged with the tools.

In the drilling of wells, particularly oil-wells and gas-wells, the string of drilling tools frequently become lodged in the well-hole in such a manner that they cannot be withdrawn by a pull upon the cable or line to which they are attached. In such cases it is necessary to lower a grab over the string of tools in a manner well known in the art, and in order to readily engage the grab or other "fishing" device with the string of tools it is necessary that the cable attached to the tools be severed close to the tools in order that it may be withdrawn from the well-hole, and thus not interfere with the fishing operation. So long as a manila or other soft rope or line was used in the drilling operation it was a comparatively easy matter to sever the same; but the use of manila or other soft rope in connection with such work has been almost entirely superseded by wire cable or line, and heretofore and before my invention it has been difficult to sever this wire cable or line at the desired point. This difficulty I effectually overcome by the provision of a tool or device having a cored body to receive the cable or line to be cut and which is lowered within the well-hole after the line has been placed therein and engages the upper end of the rope-socket carrying the string of tools. The tool in addition to the body portion embodies a plunger, the upper end of which is connected to rope-knife or sucker-rod jars and the lower end of which is

tapered and formed wedge-shaped and has a dovetail which engages in a correspondingly-shaped groove provided therefor in the rear end of the cutting-knife. This cutting-knife 55 is mounted in the body of the tool and is held normally locked in the inoperative position and is only released so that it may be forced into engagement with the wire cable or line upon the tool or device approaching in close 60 proximity to the rope-socket of the string of tools in the well-hole, at which time a trip carried by the body of the tool or device engages with the upper end of the rope-socket and releases the knife, so that it is free to be 65 forced forward under the action of the plunger into engagement with the wire cable or line.

I have now set forth briefly the objects and the principle of the invention and will proceed to describe in detail a practical form of the invention as it has been practiced by me and in such description will have reference to the accompanying drawings, forming a part of this application, and wherein like 75 numerals of reference will be employed for indicating like parts throughout the several views of the device, in which drawings—

Figure 1 is a detail side elevation of the device connected up to the sucker-rod jars and 80 showing how the device or tool is lowered into engagement with the rope-socket. Fig. 2 is a central vertical sectional view of the device, showing a part of the wire cable or line to be cut in side elevation. Fig. 3 is a horizontal 85 sectional view taken on the line 2 2 of Fig 2. Fig. 4 is a central vertical sectional view showing the plunger in the lowered position whereby to force the knife into engagement with the wire cable or line. Fig. 5 is a de- 90 tached detail perspective view of the knife. Fig. 6 is a front elevation of a part of the plunger; and Fig. 7 is a sectional view of a part of the tool, showing the trip which holds the knife in side elevation.

In so far as the device or tool itself is concerned it is of course immaterial as to how the same is connected to the operating line or cable; but I have illustrated in Fig. 1 the practical method of doing so, which is to attach the upper end of the plunger to sucker-rod jars 1, these sucker-rod jars being in turn

connected at their upper end to the lower end of the rope-knife 2, which latter is provided at its upper end with an eye 3 to receive the cable or line, (not shown,) by means of which 5 the device or tool is lowered into the well-hole and withdrawn from the same after the cutting operation has been completed.

The device or tool embodies a body portion 4, which in the present illustration is shown circular in form, though it is to be noted that it is not absolutely essential that this body portion is circular. The said body portion 4 is provided with an opening or bore 5 to receive the wire cable or line 6 to be cut. This 15 wire cable or line is suitably connected to the rope-socket 7 of the string of tools, (not shown,) and the wire cable or line is placed in the opening or bore of the body portion 4 through a slot 8 cut in the side of the tool-body. After the wire cable or line has been placed in the opening or bore in the body the side slot 8 of the body is closed by a piece 9, machined to fit neatly into the slot. In practice I preferably groove the side walls of the 25 slot 8 and provide the side walls of the piece 9 with tongues 10 to fit in said grooves. This piece is machined so that when driven into the slot in the body it would normally remain in position without locking means; but to prevent any liability of the piece being driven 30 out by engagement of its lower end with the upper end of the rope-socket I employ a locking-screw 11, inserted from the periphery of the body in such a manner as to engage both 35 the main body portion and the piece 9. Formed integral with the upper face of the body portion 4, eccentrically of said face, is an upwardly-extending barrel or sleeve 12, the opening in which is in alignment with an 40 opening or bore 14 in the body 4 and the upper end of which is shouldered off and exteriorly threaded to be engaged with the interiorly-threaded cap-nut 15, which is mounted on the plunger. Extending downwardly from 45 the lower face of the body, with its outer face flush with the periphery of the body, is a projection or guide-lip 16, provided with a concave inner face and preferably having its lower end tapered or beveled off, as shown. 50 This guide-lip extends down alongside of the upper end of the rope-socket 7 when the body of the tool engages the latter.

The body 4 of the tool is provided with a 55 knife slot or passage-way 17 underneath the bore of the sleeve or barrel 12, and mounted to reciprocate in this knife slot or passage-way is the cutting-knife for severing the wire cable or line. This knife as I have used the same in practice has preferably been in the form 60 of a substantially rectangular block 18, the edges of which are preferably rounded or beveled to slide neatly and readily in correspondingly-grooved side walls of the slot or knife-passage 17. Its inner or cutting end is beveled 65 down on one face between the side walls to form the knife-edge 19, as best seen in

Fig. 5, and at its outer end the block 18 is provided with a dovetailed groove 20 to receive a dovetailed fin carried by the plunger, as will be more fully explained hereinafter. 70 In one edge the rectangular block 18 is provided with a notch 21 to receive a locking-pin normally holding the knife retracted and acting as a trip to release the knife, whereby it may be actuated when the tool has been 75 properly positioned. To this end I tap a hole in the lower face of the body 4, extending the hole upwardly into the body for a considerable distance and the upper part of the hole being of less diameter than the lower portion, whereby an annular shoulder 22 is formed. In this hole I place the trip-pin embodying the shank 23, a part of which lies normally in the notch 21, made in the side edge of the knife, whereby to hold said knife 80 against inward movement until the trip is released. The shank 23 of the pin is provided with a notch 24 in its one side, which is preferably made of a length slightly greater than the thickness of the block 18, whereby when 85 the pin is elevated and the notch 24 comes opposite to the side edge of the knife the latter is free to be forced inwardly into engagement with the wire cable or line to be cut. This pin is provided with a squared or other 90 suitably-shaped lower end 25, which projects normally below the lower face of the body 4, whereby it will engage with the upper end of the rope-socket prior to the engagement of the lower face of the body portion with said 95 end of the rope-socket and the pin thereby be elevated to permit the knife to be operated. The pin is held in position by a plug 26, threaded into the lower end of the hole, and through which plug the squared end of 100 the pin extends, the pin being provided with an integral collar 27, which rests on the inner end of the screw-plug. The pin is normally held down, so as to lock the knife, by means of a spring 28, arranged on the pin between the annular shoulder 22 and the collar 27.

The plunger or mandrel for operating the knife to sever the wire cable or line embodies a stem 29, threaded at its upper end into a connecting member 30, which is in turn threaded at its upper end into the lower end of the sucker-rod jars 1. The cap-nut 15 is slipped onto the stem or shank of the plunger prior to connecting said stem or shank with the 110 connecting member 30, and the upward movement of the plunger is limited by an integral collar 31, the upper end of which engages the cap-nut as the plunger is elevated, while the downward movement of said plunger is limited by the engagement of the lower end of the connecting member 30 with the upper face of the cap-nut 15. This plunger, below the collar or enlargement 31, is provided with a tapered face or side 32, making the plunger 115 substantially wedge-shaped at its lower end, and centrally throughout the length of this 120

tapered face 32 is a dovetailed fin or wedge 33, which engages in the dovetailed groove 20 of the knife, whereby the latter is forced inwardly into engagement with the wire cable or line as the plunger descends and is returned to its retracted or normal position as the plunger is elevated.

In operation the piece 9 is removed, the wire cable or line 6 placed into the bore of the body, and piece 9 replaced, so as to retain the tool on the cable or line, and when the tool is connected up to the sucker-rod jars it is lowered into the well-hole. As the tool descends and approaches the upper end 15 of the rope-socket the end 25 of the trip-pin engages the upper end of the rope-socket, forcing said trip-pin upwardly within the body and bringing the notch 24 opposite the side edge of the knife, thereby releasing the lock of the latter, so that it is free to be moved inward. As the body 4 engages and rests upon the upper end of the rope-socket the plunger continues to descend, and the wedge-shaped dovetailed fin 33 engaging in 25 the dovetailed groove 20 forces the knife inwardly to engage and cut the cable or line 6 at a point in close proximity to the upper end of the rope-socket. Where the line to be cut is a light one—for instance, such as are generally employed as "sand lines"—one stroke of the knife will often sever the line, though where the line or cable is such as is generally employed for drilling or cleaning out oil, gas, or Artesian wells several strokes may be required, the jarring of the plunger forcing the knife inward into engagement with the cable or line on each descent of the plunger.

It is to be noted that the knife is securely locked by the combined trip and locking pin 40 and prevented from being forced into engagement with the line or cable until the tool has been properly positioned to cut the cable or line at the desired point, and as soon as the body is elevated away from the upper 45 end of the rope-socket the spring 28 forces the lower end of the pin beyond the lower face of the body, whereby the pin assumes a position to again securely lock the knife.

By the employment of the jars 1 it will be observed that on each upward pull on the rope or cable attached to the jars the upper member of the jars will be elevated, and as it descends and strikes the lower member of the jars the plunger will be driven 55 down farther and the knife given a farther inward thrust, this operation being continued until the severing of the cable is completed. It is to be noted that when the plunger is elevated to its full height and the knife 60 retracted to its full extent the plunger is still in engagement with the knife, and thus prevents the latter from dropping out of its slot, even if the locking-pin should be actuated at any time to disengage it from the knife.

65 While I have herein described my invention in detail as it has been practiced by me,

yet in the practice of the invention I do not desire to confine myself to the specific construction shown herein and described, as it will be evident that various changes may be 70 made in the details of construction without departing from the spirit of the invention or from the scope of the appended claims.

Having fully described my invention, what I claim as new, and desire to secure by Letters 75 Patent, is—

1. In a device of the character described, a reciprocatory knife, a vertically-movable plunger having a tapered or wedge-shaped end engaging said knife for actuating the same, 80 and means for normally locking said knife in the inoperative position.

2. In a device for cutting wire cable, a body portion adapted to receive the cable, a reciprocatory knife mounted in said body portion, 85 and a plunger having a tapering wedge-shaped end engaged with the knife and adapted on the descent of the plunger to force the knife into engagement with the cable and to retract said knife during the ascent of the plunger. 90

3. In a device for cutting wire cable, a body portion adapted to receive the cable, a reciprocatory knife mounted in said body portion, a vertically reciprocatory plunger for actuating the knife, and a combined lock for holding the knife normally in the inoperative position and for releasing the knife when the body portion has been properly positioned. 95

4. In a device for cutting wire cable, a body portion adapted to receive the cable, a knife mounted in said body portion and a plunger having a tapered wedge-shaped end for forcing the knife into engagement with the cable, substantially as described.

5. In a device for cutting wire cable, a body portion having a bore to receive the cable and provided with a slot leading into said bore, means for closing said slot to retain the cable in the bore, an extension carried by the lower face of the body portion, a reciprocatory knife mounted in the body portion to move across the bore and a vertically-movable plunger for actuating said knife, substantially as described. 105

6. In a device for cutting wire cable, a body portion provided with a bore to receive the cable, a reciprocatory knife adapted to move across the bore and normally held in the inoperative position, means for releasing said knife, and a plunger for actuating the knife 110 when released to force the same into engagement with the cable, substantially as described. 120

7. In a device for cutting wire cable, a body portion adapted to receive the cable and provided on its lower end with a guide-lip, a reciprocatory knife mounted in the body portion and normally held in the inoperative position, means projecting through the lower end of the body portion for releasing said 125 knife, and a plunger for actuating the knife, substantially as described. 130

8. In a device for cutting wire cable, a body portion adapted to receive the cable, a reciprocatory knife carried by said body portion and normally held in the inoperative position, a trip adapted when elevated to release said knife, and a plunger having a dovetailed fin engaging the knife to reciprocate the latter as the plunger ascends and descends.
9. In a device for cutting cable, a body portion to receive the cable, a reciprocatory knife carried thereby, and normally held in the inoperative position, means for releasing said knife, and a vertically-movable plunger having a wedge-shaped end for engagement with the knife to actuate the latter when released, substantially as described.
10. In a device for cutting cable, a body to receive the cable, and provided on its lower end with a guide-lug, a barrel or sleeve carried by the upper end of said body, a knife carried by the body, and a vertically-movable plunger in the barrel or sleeve, and provided with a wedge-shaped end to engage the knife and actuate the latter, substantially as described.
11. In a device for cutting cable, a body portion to receive the cable, a knife carried by the body portion, means for holding said knife normally in the inoperative position and for releasing same when the body portion has been properly positioned, and a plunger operative to move said knife against the cable during the descent of the plunger and to retract said knife during the ascent of the plunger, substantially as described.
12. In a device for cutting cable, a bored body portion to receive the cable, a guide-lip carried by the body portion at its lower end, a knife mounted within the body portion and movable across the bore, and a vertically-movable member adapted in its descent to force the knife across the bore to sever the cable, substantially as described.
13. In a device for cutting cable, a body portion to receive the cable, a knife carried by the body portion, means for holding said knife normally in the retracted or inoperative position and for automatically releasing the same when the body portion has been properly positioned, and a vertically-movable member adapted in its descent to move said knife against the cable to sever the same, substantially as described.
14. In a device for cutting wire cable, a bored cable-receiving body, a knife carried by the body and movable across the bore thereof, and a vertically-movable member having a tapering face engaging the knife and forcing the same across the bore as the member descends, substantially as described.
15. In a device for cutting cable, a cable-receiving means, a knife carried thereby, means for normally retaining said knife in the inoperative position and for automatically releasing same when the cable-receiving means has been positioned, and an actuating member engaging the knife and forcing the same into the cable as the actuating member descends, substantially as described.

In testimony whereof I affix my signature in the presence of two witnesses.
